UNITED STATES PATENT OFFICE.

COURTLAND A. DE LANO, OF CEDAR RAPIDS, IOWA.

DENTAL WAX EXPANSION CABINET.

Application filed February 25, 1927. Serial No. 170,956.

My present invention, in its broad aspect, has reference to improvements in methods and apparatus for controlling the thermal expansion and contraction of dental wax expansion and contraction of dental wax 5 patterns and investments in which the castings are made thereby to obtain more perfect castings of inlays, crowns, bridges, plates, saddles, and the like than has heretofore been attained.

10 The factors of expansion and contraction of materials from a given mean for given temperatures is a known quantity easily determinable. Heretofore the contraction of gold and other metals from the molten to 15 the solid state in castings has largely been made up by the addition of quantities of the metal during the process of cooling to make up the loss by contraction. This method has not, however, succeeded in wholly 20 compensating for variations due to thermal expansion and contraction in the wax forms or patterns and investments. Consequently perfect dental castings are obtainable only by the exercise of a high degree of skill 25 and patience.

My present method consists largely in controlling the temperature of the wax pattern or form and the investment therefore from which the casting is made so that contraction 30 in the material of the casting in its change from the molten to the solid state can be largely compensated for by expanding the wax pattern or form and the investment so that a known means will be attained which 35 will be an exact reproduction in size and details of form of the cavity, or other oral condition to be treated.

The apparatus used with my present invention consists primarily in an improved 40 and unique collapsible cabinet in which wax patterns and investments are adapted to be raised to a predetermined temperature to expand the same to the desired degree so that the final casting will be large enough to be 45 readily slipped in place free from errors due to contraction. The degree of contraction of gold from the molten state to the freezing state, and the expansion from the freezing state to normal atmospheric temperature is approximately two per cent, but 50 by careful manipulation in the casting whereby the mold is filled until the casting is solid enough to hold its form the loss due to contraction can be almost, but not quite, 55 eliminated. Consequently by properly expanding the wax pattern before the object

is cast the error factor due to thermal contraction and expansion of the metal of the casting can be compensated for (the above mentioned loss eliminated). For instance 60 when it is desired to prepare an inlay for what is termed an M. O. D. cavity (meaning a cavity on the front or mesial side, the occlusal or top side, and the distal or back side, or in other words, a cavity which is 65 somewhat U-shaped) the pattern is commonly made and the gold cast in the usual manner which gives an inlay from front to back which is so shrunken that it will not ordinarily fit the cavity. To prevent this 70 condition a copper band is placed around the tooth into which the wax is run so that when the band is filled the shrinkage is on the occlusal surface from the lingual to the buccal side, or away from the tooth and toward the 75 band. This is exactly what is wanted since by utilizing my cabinet the pattern can again be expanded to its proper form, the investment made, and the casting of the inlay completed at the proper temperature to produce in the final casting an exact reproduction 80 of the cavity.

In the drawings wherein my cabinet is illustrated:

Figure 1 is a perspective view of my 85 cabinet, the covering therefor being removed to show the interior,

Figure 2 is a perspective view of my cabinet with the cover applied thereto,

Figure 3 is a perspective view of my cabinet partly collapsed,

Fig. 4 is an end elevation,

Figure 5 is a front view of my cabinet when collapsed, and

Figure 6 is a partly diagrammatic plan 95 view of the heating units of my cabinet.

In the drawings wherein like characters of reference are used to designate like or similar parts throughout the several views;

The numeral (1) designates the base section 100 of my cabinet which has a bottom (2), a back (3) and sides (4), the front (5) is hinged thereto and has ventilating openings (6) therein. Adapted to be positioned upon the base section is a floor (7) having ventilating openings (8) therein. The floor is freely removable.

Hinged as at (9) to the back (3) of the base (1) is a back wall (10), and hinged as at (11) to the respective sides (4) are 110 side walls (12). The back wall and side walls are adapted to be locked together

along their meeting edges by fittings (13) to form a three sided compartment.

Hinged as at (14) to the back is a shelf (15), and to the top edge of the back is 5 also hinged as at (16) a relatively narrow cover element (17) which rests (when the compartment is set up) on triangular side wall extensions (18), hinged to the side walls at (18^a).

10 From the foregoing it will be seen that the compartment is collapsible by simply unlocking the fittings (13), dropping the side wall extension (18) and side walls (12) on the base sections, and dropping the cover 15 (17) and shelf (15) and the back wall (10) thereon. A swinging bracket (19) is provided for holding up the shelf (15).

The open front, and partially open top of 20 my compartment is closed by a heavy black sateen (or other material) curtain (20) having a glass covered peep opening (21) and a light fitting (22) extending to the interior of the cabinet. Another covering element 25 (23) having sleeves (24) is provided for receiving the arms of an operator, and to that end elastics (25) are provided in the edges to afford a close fit to the arms of said operator. The curtain (20) is weighted along its edges at (26) shown in dotted 30 lines, and the covering element (23) may have its edges wired (not shown) to further support the same if desired. The cover curtain (20) is separable from covering element (23) so that it may be raised to admit 35 objects to the cabinet.

The entire construction of the cabinet is of some heat resisting material such as sheet metal, composition board, or other fire resisting material.

40 In the base section (1) of my cabinet is mounted, by means of brackets (27), a tray (28) having a plurality of ventilating openings (29). On the tray are mounted sets of heating coils (30) connected with thermoelectric devices (21), and pilot lights (32) all in circuit with a detachable plug (33) with a power line (34). The elements are switch controlled as at (35) so that the heat 45 may be properly (either manually or automatically) regulated.

In operation all of the tools and instruments used in dental casting are placed in the cabinet, such as casting flasks, models, investment mixer, rubber water bottle, plaster 50 bowl, casts, patterns, brushes, slabs weighing devices, sprues, formers, pliers, and the like. These are all raised to a desired predetermined temperature and maintained at that temperature throughout the 55 whole operation of casting the inlay or the like. The operator inserts his arms through the sleeves (24) and follows his work through the peep opening (21). The temperature of the cabinet is regulated to cause 60 the proper expansion of the wax and invest-

ments to attain an absolutely accurate casting.

While I have, in the foregoing, described and illustrated the preferred embodiments of my method and apparatus with particularity, I do not desire thereby to be limited in the essential broad concept of my invention except as may be indicated by the scope of the claims appended thereunto.

I claim:—

1. A collapsible cabinet comprising a base portion, a removable floor on the base portion, a plurality of wall members hinged to the base portion to form a three sided compartment above the removable floor, triangular extensions hinged to certain of said wall members, a top hinged to the other wall members and slantly supported by the extensions when the cabinet is set up, heating elements carried by the base members, and curtaining devices removably arranged about the compartment to close the same.

2. The combination with a cabinet having a heating element therein and formed with an open side, of a weighted fabric element attached thereto to form a curtain for the open side to retain the heat in the cabinet, and another fabric element having fabric sleeve members and detached from the curtain to give access to the cabinet for a person's hand and arms, the weighted fabric element overlapping the latter fabric element.

3. A collapsible cabinet comprising a hollow base, a removable floor on the base, a plurality of wall members hinged to the base to form a compartment above the removable floor, triangular extensions hinged to certain of said wall members, a top hinged to the other wall members and slantly supported by the extensions when the cabinet is set up, heating elements carried in the hollow base, a fabric curtain covering the compartment, and fabric sleeve members giving access to the cabinet for a person's hands and arms.

4. In a dental wax expansion device, the combination of a cabinet having an open side, a pair of covering elements separate from each other and arranged one above the other, the upper covering element being weighted to normally overlap the lower element, to close the open side of the cabinet, sleeve members on the lower element for receiving a person's hands and arms and means for heating the cabinet.

5. In a dental wax expansion device, the combination of a cabinet having an open side, a pair of covering elements separate from each other and one arranged above the other in overlapping relationship to close the open side of the cabinet, the upper covering element being weighted along its lower edge, sleeve members on the lower element

for receiving a person's hands and arms and means for heating the cabinet.

6. A collapsible dental wax expansion device comprising a cabinet having a base, a back wall and two side walls hingedly connected to the base and relatively separate from each other to fold down upon the base, means for connecting the side walls with the back wall in set up position, triangular extensions hingedly connected to the side walls, 10 a top hinged to the back wall and slantingly supported by the triangular extensions and a heating element in the base.

In testimony whereof, I affix my signature hereunto.

C. A. DE LANO.
